(57) **CLAIM**

The ornamental design for a foot exercise prop, as shown and described.

DESCRIPTION

FIG. 1 is a top front left perspective view of a foot exercise prop showing my new design;

FIG. 2 is a bottom rear right perspective view thereof;

FIG. 3 is a top rear right perspective view thereof;

FIG. 4 is a bottom front left perspective view thereof;

FIG. 5 is a front elevational view thereof;

FIG. 6 is a rear elevational view thereof;

FIG. 7 is a right elevational view thereof;

FIG. 8 is a left elevational view thereof;

FIG. 9 is a top plan view thereof; and,

FIG. 10 is a bottom plan view thereof.
